BEDSIDE RAIL

Morton I. Thomas, 125 South St., Monroe, N.Y.

Filed Aug. 5, 1971, Ser. No. 169,595

Term of patent 14 years

Int. Cl. D6—06

U.S. Cl. D6—198

FIG. 1 is a side elevational view of a bedside rail showing my new design;

FIG. 2 is a top plan view thereof.

I claim:

The ornamental design for a bedside rail, substantially as shown.
